UNITED STATES PATENT OFFICE.

CHARLES A. DAHL, OF BOSTON, MASSACHUSETTS, ASSIGNOR TO THE REECE BUTTONHOLE MACHINE COMPANY, OF PORTLAND, MAINE, AND BOSTON, MASSACHUSETTS.

MACHINE FOR STITCHING BUTTONHOLES.

No. 880,496.

Specification of Letters Patent.

Patented Sept. 11, 1906.

Application filed July 1, 1903. Serial No. 163,830.

To all whom it may concern:

Be it known that I, CHARLES A. DAHL, a citizen of the United States, residing at Boston, in the county of Suffolk and State of Massachusetts, have invented an Improvement in Machines for Stitching Buttonholes, of which the following description, in connection with the accompanying drawings, is a specification, like letters on the drawings representing like parts.

This invention, relating to sewing-machines for stitching buttonholes, has for its object to provide this class of machine with means whereby the extent of relative movement of the stitch-frame or parts carrying the stitch-forming mechanism and the work holder or clamp may be readily varied in extent to provide for stitching buttonholes of different lengths.

In accordance with my invention I combine with the cam employed to impart the relative movement referred to or the longitudinal to-and-fro movement to that one of the two members, either the stitch-frame or work-holder, whichever is moved while making the overedge stitches for the sides of the buttonholes means whereby the effective length or throw of the cam may be changed to provide a longer or a shorter to-and-fro movement to the part to be moved.

I have illustrated my invention as applied to a sewing-machine such as represented in United States Patent No. 616,604, dated October 18, 1898, in which the stitch-forming mechanism is moved to and fro by a cam during the stitching of the side edges of the buttonhole and the work holder or clamp is anchored; but my invention as to certain features may be applied equally well to a machine wherein the stitch-frame is anchored and the work-holder or part carrying it is moved to and fro.

Figure 1 in side elevation represents in section a sufficient portion of one form of a buttonhole-sewing machine of well-known construction to which my improvement has been applied. Fig. 2 is an enlarged detail. Fig. 3 is a plan view of the parts shown in Fig. 2.

The bed B^2 , pivoted at 2 on supports B^{3x} , secured to a bench, the legs B^{3x} , depending from the bed at its end opposite the pivot, the work holder or clamp d^5 , mounted on the bed, the stitch or traveling frame B , sustain-

ing the usual stitch-forming mechanism, including a needle-bar having an upper needle E and a coöperating under needle E' and looper, and the buttonhole-cutting means, including a cutter C^2 and an anvil G , said frame being slidably fitted to the bed and having a depending lug h' , sustaining a stud h , about 55 which is revolved the so-called "feed-wheel" B' , having a cam-groove B^4 , are and may be all as shown and described in said patent.

Herein the stitch-forming mechanism, buttonhole-cutting mechanism, work holder or clamp d^5 , and means for actuating the same for clamping and overstitching the edge of a buttonhole and for cutting the buttonhole will be actuated as provided for in said patent.

In the machine illustrated in the patent referred to a stud carried by the bed-plate, which is stationary, enters the groove B^4 of the feed-wheel B' , and as said wheel is rotated the stitch-frame is moved to and fro 70 longitudinally, and a buttonhole of one and the same length will be produced.

In accordance with this present invention, wherein provision is made for varying the length of the buttonhole at will without removing or putting into the machine any parts and wherein I have chosen to retain the usual feed-cam, I have added to the machine means which I will now describe for the production of a buttonhole of any desired length.

Instead of the stationary stud held in the bed-plate, as in the machine described in said patent, I employ a lever a , having a stud a' . (Shown in full lines, Fig. 3, and in dotted lines in Figs. 1 and 2.) The lever is pivoted 90 on a stud-screw c , held in the lug h' , and the stud a' enters, as before, the cam-groove B^4 . The lever a has a segmental groove b' , the t receives a guide-block d , having a crank-pin d' , said block being preferably slotted, as 95 shown at d^2 , the slot being entered by a clamp-screw e , by which to clamp the block and crank-pin in adjusted position, as when it is desired to maintain the crank-pin more or less out of axial line with the stud a' . The crank-pin d' is embraced, as shown, by an arm d^3 , mounted on the stud 2.

It will be understood that the stitch-frame is the body or weight to be moved, that the crank-pin d' is the fulcrum for the lever a , and that the extent of movement of the stitch-

frame will depend upon the position of the crank-pin d' with relation to the longitudinal center of the stud a' . For instance, with the crank-pin d' and stud a' in axial alinement the stitch-frame during the rotation of the cam B^4 will travel for a length just equal to the throw of the cam. By placing the crank-pin above the stud a' the travel of the stitch-frame will be increased, and the buttonhole will be lengthened more or less, that depending on the extent of movement of said stud, and by depressing the crank-pin to a point below the stud a' the travel of the stitch-frame may be less than the stroke of the cam B^4 , and the buttonhole will be consequently shortened.

I believe that I am the first to provide a sewing-machine in which the stitch-frame or part carrying the stitch-forming mechanism and the work-holder have a relative movement with respect the one to the other for stitching a buttonhole with means carried by the moving part for varying the length of said relative movement, and I also believe that in that class of these machines in which the stitch-frame or part carrying the stitch-forming mechanism is the moving member I am the first to provide means for varying the length of said movement without the substitution of cams.

I am aware that in buttonhole-sewing machines in which the work-holder or work-clamp is moved with respect to the stitch-forming mechanism it has been customary to vary the length of the movement of said work-holder by adjusting means upon the fixed or non-moving part of the machine, and I am also aware that in buttonhole-machines where the stitch-frame or part carrying the stitch-forming mechanisms is the moving member it has been common to provide for various lengths of movement by the substitution of cams of different sizes; but my present invention differs from either of these.

Having described my invention, what I claim as new, and desire to secure by Letters Patent, is—

1. A buttonhole-sewing machine comprising a stitch-frame with stitch-forming mechanism mounted therein, a work holder or clamp, one of said members being longitudinally movable with respect to the other, means comprising a cam mounted on said movable member and connections between said cam and said fixed member for giving

said longitudinal movement, means for adjusting the connections between said cam and said fixed member whereby the length of said longitudinal movement may be adjusted and buttonholes of various lengths made. 60

2. A buttonhole-sewing machine comprising a stitch-frame with stitch-forming mechanism mounted therein, a work holder or clamp, one of said members being longitudinally movable with respect to the other; 65 means comprising a cam mounted on said movable member, a lever pivoted to said movable member and vibrated by said cam, and connections between said lever and said fixed member for giving said longitudinal movement; means for adjusting said connections upon said lever whereby the length of said longitudinal movement may be adjusted and buttonholes of various lengths made. 70

3. A buttonhole-sewing machine comprising a stitch-frame with stitch-forming mechanism mounted therein, a work holder or clamp, said stitch-frame being longitudinally movable with respect to the work-holder, a cam mounted upon the stitch-frame, connections between said cam and the work-holder whereby upon the rotation of the cam the said longitudinal movement is secured, means for adjusting said connections between said cam and said work-holder, whereby the length of said longitudinal movement may be adjusted and buttonholes of various lengths made. 80

4. A buttonhole-sewing machine comprising a stitch-frame with stitch-forming mechanism mounted therein, a work holder or clamp, said stitch-frame being longitudinally movable with respect to the work-holder, a cam mounted upon the stitch-frame, a lever pivoted to the stitch-frame and vibrated by 95 said cam, connections between said lever and said work-holder whereby said longitudinal movement is secured, means for adjusting said connections upon said lever whereby the length of said longitudinal movement may be adjusted and buttonholes of various lengths made. 100

In testimony whereof I have signed my name to this specification in the presence of two subscribing witnesses.

CHARLES A. DAHL.
